UNITED STATES PATENT OFFICE

JACQUES WALLACE D. CHESNEY, OF MILTON, WISCONSIN, ASSIGNOR TO THE BURDICK CORPORATION, OF MILTON, WISCONSIN, A CORPORATION OF WISCONSIN

THERAPEUTIC APPLIANCE

Application filed May 11, 1925. Serial No. 29,311.

This invention relates to therapeutic appliances.

It will be explained as embodied in instruments adapted for the application of radiant energy, particularly ultra-violet light rays, in the treatment of diseased conditions in body cavities.

Light rays, both visible and invisible, are extensively used in the treatment of certain 10 diseased conditions of the human body. Often the diseased condition is located partly or wholly within body cavities which are more or less curved and whose walls are more or less irregular or lie in folds of tissue.

15 Sometimes a diseased part may be located on the same side of a cavernous cavity as the external opening thereto through which an instrument may be inserted. The usual appliances heretofore employed to direct the 20 light rays from the source where they are generated, to the interior of the diseased cavity have consisted of straight or curved rods of quartz. Quartz is a good conductor of light rays, including the actinic ultra-violet rays,

25 and the greater part of the rays ordinarily will follow the axis of the rod no matter how much the same may be curved. Consequently, the greater part of the rays pass out from the end of the rod in relatively straight lines.

30 Such appliances are inefficient and ineffective in applying the rays to the side walls or folds of a cavity or passage. Furthermore, the light rays are more efficacious when they strike the surface under treatment approxi-

35 mately at right angles thereto, and with the present rods only a relatively small area directly in front of the end thereof (and it may be an area which is not diseased or relatively 40 only slightly diseased) receives the rays at approximately right angles. For the reasons thus outlined the present light applicators are inefficient and ineffective for applying the light under many conditions. The

45 object of this invention is to overcome these difficulties.

One of the objects of this invention is to provide an improved applicator.

Another object is to provide an improved 50 instrument for efficiently and effectively ap-

plying light rays to the interior walls of body cavities.

Another object is to provide an applicator whereby the light rays are deflected from their normal path therethrough and projected in the desired direction. 55

Another object is to provide an applicator which is efficient, reliable and readily manufactured.

Other objects and advantages will herein- 60 after appear.

A few embodiments of the invention are illustrated in the accompanying drawing, wherein

Figure 1 is a longitudinal section of one 65 type of straight applicator;

Figure 2 is an enlarged longitudinal section of the reflecting end of the applicator shown in Fig. 1;

Figure 3 is a section on the line 3—3 of 70 Fig. 2;

Figure 4 is a longitudinal section of a curved and modified type of applicator;

Figure 5 is a plan, partly in section, of another modified form of straight applicator; 75

Figure 6 is a partial side elevation and section of the applicator shown in Fig. 5;

Figure 7 is a longitudinal section of another modified form of curved applicator; and

Figure 8 is a section on the line 8—8 of 80 Fig. 7.

The applicator shown in Figures 1 to 3 has an elongated body 10 formed from a hollow rod of fused quartz. The rod or tube is 85 closed at both ends and, if desired, the enclosed space or chamber may be evacuate. The forward or inner end 11 of the rod is rounded so as to facilitate the forcing of the applicator into body cavities. The rear end 90 of the rod is encircled by a ferrule or collar 12 formed from suitable metal, such as brass, which may be shaped to fit a socket in the lamp housing. Ferrule 12 may be attached to the quartz body by a suitable cement, such as 95 plaster of Paris or litharge cement. A projecting lug or ridge 13 may be formed in the quartz to serve as a stop for limiting the extent to which the applicator may be inserted.

Within the rod and near its forward 100

rounded end a reflector 14 is located. Reflector 14 may be made of suitable reflecting material, such as polished nickel, and, by spinning or other well known methods of forming metal, its shape may be varied to suit different requirements. It is shown in the drawing as having a somewhat cone-shaped exterior with the apex toward the rear or lamp end of the rod,—that is, pointing in the direction from which the rays approach it. This reflector may be supported and secured in place within the rod by suitable means. In the drawing it is carried on the forward end of a metal rod or wire 15 to which it may be soldered or otherwise secured. The rear end of wire 15 is secured to the hub 16 which, by means of spokes 17, is carried at the center of a split metal ring 18. The ring 18 fits the bore of tube 10 and may be held in place by a ridge 19 formed in the quartz.

Most of the light rays from the lamp will pass longitudinally or axially through the space in the elongated rod until they encounter the reflecting surface of reflector 14. The reflector will deflect the rays in such a way that they will pass outwardly through the quartz wall of the rod as shown in Figure 2 instead of passing out at the end of the rod as was the case with prior applicators.

Figure 4 shows a modified construction embodied in a curved applicator. The body of this applicator comprises a rod 20 formed of metal, such as brass tubing. The lamp or rear end of the metal tube is closed and sealed by a quartz plug 21. A quartz plug 22 is fitted into the curved forward end of the rod so as to seal the same and, on account of the peculiar property of quartz herefore mentioned, to direct the light rays around the curve. Suitable cements, such as those previously mentioned, may be used to secure the quartz plug to the metal tube and the external chamber may or may not be evacuated as desired.

The forward end of plug 22 is formed to accommodate any desired shape of reflector 23, such as the inverted cone shown, and this surface is coated with a suitable reflecting material. It has been found that a satisfactory reflecting surface can be applied to the quartz as follows: Prepare a solution A by dissolving silver nitrate in distilled water; then precipitate the silver with ammonia and finally add sufficient ammonia water to dissolve the silver precipitate. Prepare a solution B by dissolving Rochelle salts in distilled water and add a small amount of silver nitrate solution. The quartz surface to be plated or coated, after being thoroughly cleaned and freed of grease, is dipped into a solution composed of equal parts of solutions A and B.

A hollow rounded-end fused quartz tip 24 is fitted upon the exposed end of quartz plug 22 and fused thereto. This tip serves to pro-

tect the reflecting surface 23 and to provide a smooth rounded end to facilitate the forcing of the applicator into a body cavity. The junction of the metal tube 20 and quartz tip 24 preferably should be far enough back from the reflecting surface so that all or most of the deflected rays can pass out through quartz instead of encountering the obstruction of the metal tube.

It has been found that when curved quartz applicator rods become wet, as usually happens, for example when they are inserted into the throat, the tendency of the rays to follow the axis and pass around the curve is very materially lessened. Under such conditions a relatively large percentage of the rays will continue in substantially their original direction and will escape from the rod at the curve. The sheathing of the quartz at the curve by the metal tube prevents the same from becoming wet and preserves the desirable ray-directing characteristics of the dry quartz.

Figures 5 and 6 show another modification wherein a reflector 25 shaped somewhat like the bowl of a spoon is located in the forward closed end of a hollow quartz rod 26. Such a reflector will not only deflect the rays outwardly through the side walls of the quartz rod, but will serve to collect and concentrate them into a reduced area and thereby magnify their effect. Reflector 25 may be supported by a metal strip 27 and split ring 28 which may be formed integrally therewith.

Figures 7 and 8 show another modified type of curved applicator wherein a reflector instead of curved quartz is utilized to direct the rays around a curve. The body of the applicator comprises a quartz rod 30 into the forward curved end of which is fitted and cemented a curved tube 31 of suitable reflecting metal, such as polished nickel. This reflector serves to deflect the rays around the curve. After the reflector is in place, the end of the applicator tube may be closed and sealed by a rounded quartz tip 32 fused to the end of quartz tube 30. The space or chamber within the rod may then be evacuated, if desired.

The various structures which have heretofore been described and shown in the drawings represent but a few of the modifications which may embody the characteristics of this invention. The shapes and sizes of the applicators may be varied as desired or as necessitated by particular uses to which they may be put. The reflectors likewise may be varied in shape and characteristics so as to deflect the rays at any desired angles from their normal paths, and to collect or concentrate them or to diffuse them over a greater area or to deflect them along substantially parallel lines. Instead of making the rods of quartz or metal tubes, solid quartz rods may be used to good effect in some situations and

the reflecting surfaces applied directly to properly shaped surfaces therein. The term "rod" as used in this specification and in the appended claims is intended to include both 5 solid rods and hollow rods, the latter being commonly referred to in the art as tubes.

I claim:

1. A therapeutic appliance comprising a hollow rod through which light rays pass 10 axially, a reflector positioned in the rod to deflect the rays, and a support for securing the reflector in position in the rod.

2. A therapeutic appliance comprising a hollow rod through which light rays may be 15 transmitted into body cavities, and a reflector within the rod for deflecting the light rays at an angle to the adjacent longitudinal axis of the rod.

3. A therapeutic appliance comprising a 20 supporting body adapted to extend into a body cavity, said supporting body including a transparent member adapted to transmit radiant energy, and a deflector carried by said supporting body and adapted to deflect 25 radiant energy through said transparent member.

4. A therapeutic appliance comprising a supporting body adapted to extend into a body cavity, said supporting body including 30 a transparent member adapted to transmit radiant energy, and a deflector carried by said supporting body and adapted to deflect radiant energy through said transparent member, said supporting body including an 35 elongated quartz member for transmitting radiant energy to said deflector.

5. A therapeutic appliance comprising a supporting body adapted to extend into a body cavity, said supporting body including 40 a transparent member adapted to transmit radiant energy, a deflector carried by said supporting body and adapted to deflect radiant energy through said transparent member, said supporting body including an elongated quartz member for transmitting radiant energy to said deflector, and said quartz member being curved to transmit radiant energy about irregularities in said cavity.

6. A therapeutic appliance comprising a 50 supporting body adapted to extend into a body cavity, said supporting body including a transparent member adapted to transmit radiant energy, a deflector carried by said supporting body and adapted to deflect radiant energy through said transparent member, said supporting body including a quartz member for transmitting radiant energy to 55 said deflector, and a rounded tip of the same material as said transparent member to prevent injury in the insertion of said appliance.

7. A therapeutic appliance comprising a supporting body adapted to extend into a body cavity, said supporting body including a transparent member adapted to transmit 65 radiant energy, a deflector carried by said

supporting body and adapted to deflect radiant energy through said transparent member, said supporting body including a quartz member for transmitting radiant energy to said deflector, and a shield for preventing 70 wetting of parts of said quartz member.

8. A therapeutic appliance comprising a supporting body adapted to extend into a body cavity, said supporting body including a transparent member adapted to transmit 75 radiant energy, a deflector having a surface of revolution, carried by said supporting body, a quartz member for transmitting radiant energy to said deflector, said quartz member being curved, and said supporting body including a shield for preventing wetting of certain parts of said quartz member, and a rounded tip of quartz on said supporting body.

In witness whereof, I hereunto subscribe my name this 24th day of April, 1925.

JACQUES WALLACE D. CHESNEY.
